UNITED STATES PATENT OFFICE

JOSEPH D. BATES, OF WESTFIELD, MASSACHUSETTS.

DISH OR PLATE.

SPECIFICATION forming part of Letters Patent No. 730,082, dated June 2, 1903.

Application filed April 3, 1900. Renewed November 6, 1902. Serial No. 130,200. (No model.)

To all whom it may concern.:

Be it known that I, JOSEPH D. BATES, a citizen of the United States of America, and a resident of Westfield, in the county of Hampden and State of Massachusetts, have invented certain new and useful Improvements in Dishes or Plates, of which the following is a full, clear, and exact description.

This invention relates to an improved plate or similar dish of a class comprising two parts or sections, one of which is a metallic or otherwise suitably rigid, durable, and permanent holder or support, while the other section, which is very thin and may be composed of hard, strong, and tough paper and is adapted to be nested in the holder or permanent section, is for temporary employment, to be thrown away after once using and to be replaced by another new or fresh one the next time the dish is to be used.

The improved-dish is advantageous for the use of campers, picnic parties, or yachtsmen, who are enabled to have satisfactory plates or dishes for their lunches or dinners and to throw away the paper or other thin sections without experiencing any mentionable loss and to be thereby relieved of the inconvenience of dish-washing.

The invention is fully described hereinafter in connection with the accompanying drawings and is set forth in the claims.

Referring to the drawings, Figure 1 is a plan view of the improved plate or dish, shown as having a portion thereof broken away and in section for the purpose of increased clearness of illustration. Fig. 2 is a sectional view taken on line 2 2, Fig. 1. Fig. 3 is a sectional view of a stack or tier of the renewable dish-sections nested. Figs. 4 and 5 are perspective views of edge portions of the dish, showing peculiarly-recessed formations thereof, hereinafter referred to.

Similar characters of reference indicate corresponding parts or formations in all the views.

In the drawings, A represents the permanent or base section of the two-part dish, and B represents the inner and renewable section. The said part A may be made quite thin; ad-

vantageously of sheet metal, and of the ordinary form of a plate or other dish.

The parts B are preferably made of paper, being cut out into the form of disks and by the use of dies or otherwise formed with an upturned marginal portion b to correspond to the marginal portion a of the form or permanent dish-section A. The form and dimensions of the parts B are made conformable to those of part A, so that the former may fit closely within the latter, as shown in Figs. 1 and 2.

As a means of engagement between the renewable sections or disks and the forms or base-section the latter has several marginal recesses d, the opposite edges 10 of which are inclined or convergent from the inner edge of the recess outwardly, as seen in Fig. 4, or such inclinations or convergence may be reversed, as seen in Fig. 5, while the renewable dish-sections B have marginal tabs or ears f as wide as the maximum width of said recesses d, so that when the section B is nested in the base-section A said ears may be crowded into and interlocked with the edges of said recesses. This may be readily done with the thumb or finger.

The inner sections may be composed of ordinary paper solely or paper treated by any of the processes known in the arts for rendering it waterproof or extraordinarily hard and tough.

It will be appreciated that a plentiful supply of the sections or disks B may be nested into very compact form for stowage or transportation, and their nature is such that they are not liable to become cracked or broken, as is the case with the well-known thin wooden or veneer plates now in common use.

Having thus described my invention, what I claim, and desire to secure by Letters Patent, is—

1. As a new article of manufacture, the dish or plate composed of the permanent section A having edge recesses and the renewable inner section B of paper or like thin material having outwardly-extending marginal ears or tabs f, adapted to engage in said recesses, substantially as described.

2. As a new article of manufacture the dish or plate composed of the permanent section A having marginal recesses, the opposite edges of which are inclined relatively to each other, and the renewable paper section B adapted to the shape and size of the permanent section A to be nested therewithin, and provided with the marginal integrally-formed

ears or tabs *ff*, for engagement in said recesses, substantially as described.

Signed by me at Springfield, Massachusetts, this 31st day of March, 1900.

JOSEPH D. BATES.
